CRACKING HYDROCARBONS IN THE PRESENCE OF BROMINE-CONTAINING TERPENIC COMPOUNDS

Hillis O. Folkins, Skokie, Ill., assignor to The Pure Oil Company, Chicago, Ill., a corporation of Ohio

No Drawing. Application December 14, 1944, Serial No. 568,197

14 Claims. (Cl. 196—52)

1

This invention relates to a method for conversion of hydrocarbons and more particularly to a method for converting higher boiling hydrocarbons into lower boiling hydrocarbons and/or into less saturated hydrocarbons.

I have discovered that terpenes and camphors, particularly the cyclic terpenes and camphors or related compounds having one or more halogen atoms, particularly bromine, in the molecule are highly effective in promoting the decomposition of hydrocarbons when mixed in small amounts with the hydrocarbons undergoing decomposition.

One of the objects of this invention is to provide an improved method for converting hydrocarbons into lower boiling hydrocarbons and/or into hydrocarbons of less saturation.

Another object of the invention is to accelerate the rate of cracking of hydrocarbons.

Still another object of the invention is to provide a method for increasing the yield of cracked hydrocarbons in conventional type cracking operations.

Still a further object of the invention is to produce motor fuel of increased octane number.

Other objects of the invention will become manifest from the following description.

In accordance with my invention, hydrocarbons are mixed with a small amount of a terpene or camphor or a mixture thereof having one or more halogen atoms in the molecule. Compounds having more than one halogen atom in the molecule are preferred. As examples of halogenated terpenes and camphor type compounds which may be used in the invention are:

d-Limonene tetrabromide
Dipentene tetrabromide
Bromo-menthone
1,4,8 tribromo p-menthane
d-Carvone hydrobromide
d-Bromocamphor
2-bromocamphane-3 carboxylic acid
 α -bromocamphene
Bromofenchone
Bromoepicamphor
Bromonitrocumphane
Bornyl bromide
Chlorobromocamphane
Pinene dibromide

In addition to the halogenated terpenes and

2

camphors, halogenated derivatives thereof such as esters, ethers and amino, nitro, alkyl, aryl and aralkyl derivatives in which the aforesaid groups are substituted for one or more hydrogen atoms in the molecule may be used. The brominated terpenes and camphors and derivatives thereof give good results when used in amounts of approximately .05 to 5% by weight of hydrocarbons undergoing cracking, although smaller amounts may be used. I prefer not to use in excess of 3% by weight, since amounts below 3% provide satisfactory acceleration of the cracking reaction without causing the presence of objectionable amounts of undesirable compounds in the resulting product. Generally speaking, 1% or less of the brominated compound is adequate.

Instead of using pure halogenated terpenes and camphors, or derivatives thereof, I may use substances rich in any of the aforesaid compounds and halogenate the substances. As an example, brominated turpentine provides a satisfactory sensitizer since turpentine is largely alpha and beta pinene.

Although the aforesaid sensitizers are primarily useful in cracking hydrocarbon oils boiling above the gasoline boiling range, in order to produce gasoline, or in cracking gasoline-boiling range hydrocarbons to produce gasoline of higher anti-knock value, the invention is directed also to the cracking of hydrocarbon gases such as propane or butane in order to produce unsaturated hydrocarbons.

Sensitizers, in accordance with my invention, are useful in conventional thermal cracking processes at atmospheric, sub-atmospheric or super-atmospheric pressure. Cracking of hydrocarbon oils and gases may be carried out within the temperature range of approximately 650 to 2000° F., depending on the nature of the charging stock and the type of product desired. Where cracking of hydrocarbon oils to gasoline is practiced, the temperature may range from approximately 650 to 1200° F. When cracking gases or oils in order to form aromatics, temperatures of approximately 1000-1500° F. may be resorted to. Where it is desired to crack hydrocarbon oils and gases to butadiene, a temperature of approximately 1300 to 1600° F. may be used. Where cracking of oils or gases to low molecular weight gaseous hydrocarbons is desired, temperatures of the order of 1500 to 2000° F. may be used.

In practicing the invention, the halogenated cyclic terpenes, camphors, or derivatives thereof, may be mixed with the hydrocarbons to be charged to the process prior to entrance thereof into the reaction zone, or the sensitizer may be flash-injected directly into the reaction zone, after heating sufficiently to either melt or vaporize the sensitizer. Where flash-injection is practiced, care should be exercised not to heat the sensitizer above its decomposition temperature prior to its injection into the reaction zone.

In order to demonstrate the effectiveness of sensitizers herein disclosed, a series of runs was made using Pennsylvania gas-oil as charging stock in a continuous laboratory cracking operation. The runs were carried out at a temperature of approximately 977° F. and at atmospheric pressure. In three of the runs d-bromocamphor was used as sensitizer in different amounts. A blank run was made in order to form a basis of comparison and a run was made with bromine in order to show the effectiveness of d-bromocamphor as a sensitizer.

The results of the several runs are given in the following table:

Table I

	Run No. 24-G	Run No. 28-G	Run No. 21-G	Run No. 22-G	Run No. 23-G
Temperature, ° F.	977	977	979	977	979
Pressure	atm.	atm.	atm.	atm.	atm.
Charge gms./hr.	165.2	164.8	165.2	164.8	164.0
Sensitizer		bromine (0.1% by wt.)	d-bromo-camphor (1.0% by wt.)	d-bromo-camphor (0.5% by wt.)	d-bromo-camphor (0.1% by wt.)
Liquid Products, gms./hr.	156.4	152.8	145.2	148.4	152.0
Gas Products, gms./hr.	9.1	14.2	19.0	15.7	12.1
Liquid Products below 400° F., Per Cent of Charge:					
Vol.	12.5	14.6	24.6	19.3	15.7
Wt.	11.2	13.1	22.3	17.2	14.8
Liquid Products above 400° F., Per Cent of Charge:					
Vol.	83.0	78.2	65.3	72.4	77.9
Wt.	83.3	78.4	66.1	73.2	77.8
Gas Produced, Wt. Per Cent of Charge.	5.5	8.5	11.6	9.6	7.4
Specific Gravity of Gas	1.079	1.331	1.227	1.176	1.100

From the table it will be seen that without any sensitizer being present (run No. 24-G), the yield of gasoline (liquid below 400° F.) was 11.2% and the total yield of products below 400° F. was 16.7%.

When 0.1% by weight of bromine was present (run No. 28-G), the yield of gasoline was 13.1% and the total yield of products boiling below 400° F. was 21.6%.

Run No. 23-G made with 0.1% by weight of d-bromocamphor as sensitizer gave a gasoline yield of 14.8% and a total yield of products boiling below 400° F. of 22.2%. Thus, d-bromocamphor not only excels bromine on a weight for weight basis, but considering the small amount of bromine present in the compound, the compound is remarkably effective.

Run No. 22-G made with 0.5% by weight of d-bromocamphor produced a gasoline yield of 17.2% by weight, and run No. 21-G using 1.0% by weight of d-bromocamphor produced a gasoline yield of 22.3%, almost twice the yield obtained without any sensitizer. Likewise the yield of total products boiling below 400° F., with 1.0% by weight of d-bromocamphor was 33.9, whereas it was 16.7% without any sensitizer.

Another series of runs was made using Pennsylvania gas-oil as charging stock under a pressure of 500 pounds per square inch in which the temperature was kept at approximately 887° F. during each run. The results on these runs are tabulated in Table II.

It is apparent from Table II that even when 45 as little as .05% by weight of d-bromocamphor was used, an increase of approximately 18% in yield of liquid hydrocarbons boiling up to 400° F. was obtained. It is also evident from Table II that the liquid product boiling within the gasoline line boiling range obtained, using d-bromocamphor as sensitizer, is higher than the octane number of the gasoline obtained without sensitizer. Thus, not only do sensitizers within the scope of the invention produce more gasoline than can be produced without sensitizer under similar cracking conditions, but they also produce gasoline of higher octane rating.

Although my invention is applicable to all known types of thermal hydrocarbon cracking processes, including catalytic and purely thermal, it is particularly adapted for use in connection with thermal operations in which no solid catalyst is used. The invention may be used in present types of thermal cracking processes and apparatus without modifying such processes or the apparatus in which they are conducted, except to the extent necessary to provide for the introduction of the sensitizer at some point in the operation prior to the time the products leave the reaction zone.

It is to be understood that my invention is directed to the use of brominated terpenes and camphor type compounds, regardless of whether groups or elements other than bromine are attached to the terpene or camphor rings, and is

more particularly directed to brominated polycyclic terpenes, camphors and their derivatives.

It is claimed:

1. The method of cracking hydrocarbons comprising subjecting said hydrocarbons to suitable cracking conditions in the presence of a small amount of a substance selected from the group consisting of bromine-containing terpenes, camphors, their esters and ethers, and amino, nitro, alkyl, aryl, or aralkyl derivatives thereof.

2. The method of cracking hydrocarbons comprising subjecting said hydrocarbons to temperatures of approximately 650° to 2000° F. in the presence of a small amount of a substance selected from the group consisting of bromine-containing terpenes, camphors, their esters and ethers, and amino, nitro, alkyl, aryl or aralkyl derivatives thereof.

3. The method of cracking hydrocarbons containing a major proportion of propane comprising, subjecting said hydrocarbons to temperatures of approximately 650° to 2000° F. in the presence of a small amount of a substance selected from the group consisting of bromine-containing terpenes and camphors, their esters, ethers, and amino, nitro, alkyl, aryl, or aralkyl derivatives thereof.

4. The method of cracking hydrocarbons boiling above the gasoline boiling range comprising, subjecting said hydrocarbons to temperatures of approximately 650° to 2000° F. in the presence of a small amount of a substance selected from the group consisting of bromine-containing terpenes and camphors, their esters, ethers, and amino, nitro, alkyl, aryl, or aralkyl derivatives thereof.

5. The method of cracking higher boiling hydrocarbon oils to hydrocarbons within the gasoline boiling range comprising subjecting said oils to cracking at temperatures of approximately 650 to 1200° F. in the presence of approximately .05 to 3% by weight of a substance selected from the group consisting of bromine-containing terpenes, camphors, their esters and ethers, and amino, nitro, alkyl, aryl, or aralkyl derivatives thereof.

6. The method of cracking higher boiling hydrocarbon oils to hydrocarbons within the gasoline boiling range comprising, subjecting said oils to cracking at temperatures of approximately 650° to 1200° F. in the presence of approximately 0.05 to 3 per cent by weight of a bromo-camphor.

7. The method of cracking higher boiling hydrocarbon oils to hydrocarbons within the gasoline boiling range comprising, subjecting said oils to temperatures of approximately 650° to 1200° F. in the presence of approximately 0.05 to 3 per cent by weight of d-bromocamphor.

8. The method of cracking higher boiling hydrocarbon oils to hydrocarbons within the gasoline boiling range comprising, subjecting said oils to temperatures of approximately 650° to 1200° F. in the presence of approximately 0.05 to 3 per cent by weight of dibromocamphor.

9. The method of cracking hydrocarbon oil boiling above the gasoline range comprising subjecting said oil to a temperature of approximately 977° F. in the presence of approximately .1 to 1% by weight of d-bromocamphor for a period of time suitable for cracking a substantial portion of said oil to gasoline boiling hydrocarbons.

10. The method of cracking hydrocarbons comprising, subjecting said hydrocarbons to suitable cracking conditions in the presence of a small amount of a bromine-containing cyclic terpene.

11. The method of cracking hydrocarbons comprising, subjecting said hydrocarbons to temperatures of approximately 650° to 2000° F. in the presence of a small amount of a bromine-containing cyclic terpene.

12. The method of cracking higher boiling hydrocarbon oils to hydrocarbons within the gasoline boiling range comprising, subjecting said oils to temperatures of approximately 650° to 1200° F. in the presence of approximately 0.05 to 3 per cent by weight of a bicyclic terpene containing at least one bromine atom in the molecule.

13. The method of cracking hydrocarbons comprising, subjecting said hydrocarbons to suitable cracking conditions in the presence of a small amount of a bromine-containing camphor.

14. The method of cracking hydrocarbons comprising, subjecting said hydrocarbons to suitable cracking conditions in the presence of a small amount of a bromine-containing polycyclic terpene.
